SAFETY MECHANISM

Raymond F. Manke, Racine, Wis., assignor to
Walker Manufacturing Company of Wisconsin,
Racine, Wis., a corporation of Wisconsin

Application August 30, 1946; Serial No. 693,975

11 Claims. (Cl. 254—135)

1

The present invention relates to hoisting devices, particularly for motor cars and wheeled vehicles, and has as its principal object the provision of improved and simplified safety locking means for vehicle lifts of the four post, cable-operated type, of the general character disclosed in the co-pending application of Fred C. Haumer-
son, Serial No. 737,609, filed March 27, 1947.

In the operation of lifts of the above-indicated type, and of other varieties, the load is sustained by wire rope or cables. While commercially available cable is of such reliable and uniform character that the danger of failure is extremely remote, even in the event of long-continued neglect or abuse, it is highly desirable to guard against even such a remote contingency, since men must usually work directly beneath the lift, and a failure might cause damage to valuable property even if it did not result in severe injury or death to the workman. The present invention accordingly has as its principal object to provide improved, extremely simple, rugged, reliable and quick-acting safety means adapted to positively prevent the load from dropping in event of cable failure.

Another important object of the invention is to provide such safety means constituting supplemental manual hoist-operating means whereby the load may be safely and slowly lowered by hand after a cable failure.

Other objects and advantages will be apparent upon consideration of the present disclosure in its entirety.

In the drawings:

Fig. 1 is a perspective view of a cable-operated lift provided with safety means constructed in accordance with the present invention;

Figs. 2A and 2B are vertical sectional elevational views, partially broken away, taken substantially centrally through one pair of corner posts and the side rail connecting the same, these views being adapted to be read in juxtaposition, with Fig. 2A at the left, the upper, winch-containing portion of the mechanism being shown on a somewhat reduced scale in Fig. 2A.

Fig. 3 is a sectional elevational view of a part of the safety mechanism, showing the parts in the positions they assume in the event of cable failure; and

Fig. 4 is a fragmentary cross section taken substantially on the line 4—4 of Fig. 3 and looking in the direction of the arrows.

Referring now to the drawings, reference characters 1, 2, 3 and 4 designate generally the corner posts of the lift structure, the general construc-

2

tion of which corresponds to that disclosed in the co-pending application above referred to. In its broader aspects, however, the invention is not restricted to details of construction of the lift, which may be varied within wide limits without departing from the essential attributes of the present invention. Such details will therefore only be considered herein to the extent necessary for a complete understanding of the present invention.

The load-supporting platform consists of a framework including parallel longitudinal side rails 6, 8, the spacing of which exceeds the width of the widest vehicle or load for which the lift is designed. Side rail 6 extends between the corner posts 1, 2, and side rail 8 extends between the corner posts 3, 4. The posts 1, 3 are considered the front posts, while posts 2, 4 are termed the rear posts; the posts being designated in the manner indicated for the reason that conventionally constructed rear-drive vehicles to be lifted are customarily driven front-first onto the hoist between the posts 2, 4. The arrangement of the right-hand and left-hand post and rail assemblies being similar in most respects, this description will be confined to one side of the structure, except for such essential features of difference as exist between the right and left assemblies. The front end of each rail is provided with a fitting 10 extending through elongated vertical slot 14 and into the interior of the post 1 and guided by such slot 14 during raising and lowering of the lift to prevent lateral displacement of the rail. A somewhat similar fitting, as 12, is carried by the rear extremity of each rail as 6, and projects through a similar slot as 16 in the rear post as 2. The rails are thus positively restrained against lateral displacement, as will be apparent. The side rails are of hollow, box-like cross section and interiorly communicate at their ends with the interiors of the respective corner posts, which are also of hollow rectangular cross section.

Mounted at the tops of the front posts 1 and 3 are winch means, powered by an electric motor M mounted on the post 1. The winch means carried by the post 1 comprises a windlass drum 18 driven by the motor through reduction gearing generally designated 20. A similar drum (not shown) mounted coaxially with the drum 18 within a housing 22 carried by the top of the post 3 is driven synchronously with drum 18 by a cross-connecting shaft 24. A lifting cable 26 is wrapped about and secured at its end to each drum as 18, and actuatable thereby in the usual manner. The cable extends downwardly from the drum

through the post 1, under a sheave 26 carried by the rail end fitting 19, longitudinally through the rail 6, beneath a second guide sheave 28 mounted in the fitting 12 at the rear end of the rail, and upwardly through the post 2 to an anchorage of the shock-absorbing type, generally designated 30, at the upper end of post 2. It will be seen that the cable and pulley arrangement described forms a sling-type support for the rail 6, and it will be understood that similar lifting means (not shown) is incorporated within the posts 3, 4, and the side rail 8 so that the rails 6, 8 may be raised and lowered in parallel relation by their respective windlass drums.

Cross tie members as 32, 34 connect the side rails near their front and rear extremities, and carry load-supporting means such as the pans 35, 37 which may be arranged to receive the wheels of a vehicle to be lifted. The front pans 35 and their ties 32 may be movable lengthwise of the rails 6—8 to accommodate the lift to different vehicle wheel bases.

In order to prevent the rails 6, 8 and the lifting frame carried thereby from tilting about a transverse axis in event a greater proportion of the load is positioned forwardly or rearwardly of the center of gravity of the lifting frame assembly, stabilizing means is housed in each of the front posts 1, 3, each such stabilizing means consisting of a vertically disposed looped chain-cable assembly constructed as illustrated in Fig. 2A and including a chain section 40 meshing with and drivable by a sprocket 42, the sprocket being coaxial with respect to the drum 18 and drivable as a unit therewith by the motor M. The rear leg of the chain 40 is coupled at its lower end to a bracket portion 44 rigidly carried by and shown as formed integrally with rail end fitting 10 within the post 1, while the cable portion 41 which forms the lower continuation of the chain is also coupled to the bracket portion 44 and extends downwardly therefrom, beneath the guide sheave 45 and upwardly near the front of the post to connection with the front leg of the chain to form a closed loop. It will be seen that a complete chain loop might be employed, rather than substituting cable in the lower section of the loop in the manner disclosed, although the use of cable in the lower portion is preferred since it simplifies the lower guiding sheave means 45 and is somewhat quieter in operation. The coupling means for the rear legs of the coaxial chain-cable portions is designated 46.

Since a two-to-one speed reduction of the drive imparted to the lifting frame is effected by the single sling support arrangement, the diameter of the sprocket 42 is half that of the drum 18, and the front end of rail 6 is accordingly driven by the chain at the same rate as the average driving speed imparted to the rail by the main cable 25. Differential driving of the rail, and consequent tilting of the same about a transverse axis due to unequal loading, is prevented, however, by the positive driving connection provided by the chain and sprocket drive. The lifting frame assembly is accordingly positively maintained in horizontal position at all times since, as previously indicated, similar stabilizing means is also associated with the other side rail 8 within the corresponding front post 3.

The motor M is not drivable by the load, whether or not the motor is energized. It will be recognized that such an irreversible drive may be provided in any of various ways, as by the design of the gear reducing means 20, or by the

provision of friction drag means acting upon the motor shaft, so that the effect of the drag upon the motor is relatively slight, but is multiplied by the gearing to render the drive irreversible. In the construction shown, such a friction drag is incorporated but not illustrated, since it forms no part of my present invention. It may be housed within the supplemental casing portion 50 mounted on the post 1 and supported by the winch housing portion 38 carried by the top of the post. The details of a suitable friction brake of this character are disclosed in Willard T. Walker Patent No. 1,958,026, issued May 8, 1934, although it will be appreciated that any suitable design might be employed. By reason of the irreversible character of the windlass drive, the stabilizing means in the front posts not only function whether or not the motor is energized, but serve as safety mechanism adapted to sustain the front ends of the rails 6, 8 in event of failure of one or both of the main cables.

Automatic safety means are also provided arranged to prevent dropping of the rear ends of the rails in event of such a cable failure. It will be appreciated that each of the posts 2, 4 incorporates an independent safety device although only the device within post 2 is illustrated. As shown in Fig. 2B, the vertically disposed screw shaft 52 is mounted within the post 2 and provided with helical threads extending the full length of the vertical travel of the lift. The screw shaft is supported at its upper end by means of a rigid bracket 54 welded or otherwise secured in place and also serving to support the anchoring means 30 for the main cable 25. The screw shaft is provided with a squared upper extremity as 56, or otherwise suitably contoured to receive a hand crank or wrench (not shown) and is provided with a shoulder shown as formed by a welded-on washer 58 overhanging the bracket 54 and preventing downward movement of the shaft but permitting the same to be rotated about its longitudinal axis. The bracket 54 may be reinforced beneath the portion thereof which supports the shaft, as by means of the relatively heavy angle bracket 60. The shaft depends through a tubular guide portion 62 carried by and shown as formed integrally with the rear end fitting 12 of the rail 6, the smooth cylindrical inner surface of tubular portion 62 being proportioned to slide freely over the surface portions of the helical thread of the shaft. It will be noted that shaft 52 is spaced from but extends parallel to the portion of the cable 25 which projects upwardly through the post 2, when the cable is in its normal operating position.

A lever-type locking dog 65 is pivoted in the fitting 12 upon a cross pin 66, located between the aforementioned vertical portion of cable 25 and the shaft 52 and rockable substantially in a plane passing through the axes of both the cable and shaft. At its lower extremity the dog is provided with teeth 68 proportioned to interfit with those of the shaft when moved into engagement therewith by counterclockwise rotation of the dog, as viewed in Fig. 2B. The upper arm of the dog carries a roller 70 which normally engages the aforementioned vertical portion of the main cable 25, thereby holding the toothed portion 68 out of engagement with the shaft 52. In normal operation of the lift, the roller 70 moves freely up and down the cable 25 while the tubular portion 62 slides freely over the shaft 52. The toothed portion 68 is constantly urged toward the shaft 62, however, by a helical com-

pression spring 72 trapped in coacting opposite and inwardly facing socketed portions (undesignated) formed in the upper portion of the dog and the opposed inwardly facing portion of the tubular section 62, respectively. It will be appreciated that so long as the main cable remains in its normal operating condition, the dog cannot rock to a position to permit teeth 68 to engage those of the shaft, but that in event of failure of the cable, its resultant slackening immediately permits counterclockwise rotation of the dog, as viewed in Fig. 2B, under the influence of spring 72, so that the teeth 68, engaging the teeth of the shaft 52 which is held by the walls of the tubular portion 62 against movement away from the dog 65. The shaft 52 will thereby assume and sustain the load of the rail 6, preventing the same and the load carried thereby from dropping appreciably.

In order to lower the load after such a cable failure, it is only necessary to apply a crank, wrench or other suitable rotating means to the squared upper extremity 56, and turn the screw shaft 62 in a direction to lower the dog 65, the toothed portion 68 of which then serves as a nut permitting the rear end of rail 6 and the connected load-sustaining framework to be manually lowered. The cover portion 80 which is carried at the top of post 2 is removable to afford access to the crank-receiving portion 56. It will be appreciated also that in order to lower the front portion of the rail 6, and the rail 8, assuming that the cable for the rail 8 has not failed, the motor M may be operated slowly or intermittently, at a rate corresponding to the downward actuation of the rear end of rail 6 by the manual means just mentioned, whereupon the front end of rail 6 will be lowered through the chain-cable stabilizer means previously described, while the rail 8 is lowered by its cable and windlass means in the normal manner and at the same rate.

While it will be apparent that the preferred embodiment herein described is well calculated to achieve the objects and advantages first above stated, it will be apparent that the invention is susceptible to variation, modification, and change within the spirit and scope of the subjoined claims.

Having thus described the invention, I claim:

1. In combination with a lift mechanism of the cable-operated type comprising a main cable including a normally taut portion, and load-supporting means actuatable by such cable, safety means for preventing unwanted falling of such load-supporting means in event of cable failure, comprising an elongated supplemental holding abutment member rigidly supported in a position parallel to the normal path of movement of such load-supporting means, safety holding means including a lever pivoted to said load-supporting means and movable to and from engagement with said abutment member, said lever having a portion adjacent said normally taut portion and engageable therewith and actuatable by said taut portion for normally maintaining said holding means out of engagement with said abutment member, and means rendered effective as a result of the slackening of the cable taut portion for moving said holding means into a position to engage said abutment member.

2. Means as set forth in claim 1 in which said abutment member is provided with a plurality of abutment portions serially arranged therealong,

and said holding means is engageable with any of such portions in accordance with the longitudinal positioning of the load-supporting means.

3. Means as set forth in claim 1 in which said abutment member comprises a screw shaft rotatable about its axis but held against unwanted longitudinal displacement and provided with thread means of irreversible pitch, said holding means being engageable with said teeth to serve as a locking dog, and being held against rotation with the shaft whereby the holding means may serve as a nut to enable actuation of the load-supporting means by rotation of the shaft.

4. In combination with a lift mechanism of the cable-operated type comprising a main cable including a normally taut portion and load-supporting means actuatable by such cable, combined safety means and manual operating means for controlling the descent of such load-supporting means in event of cable failure, comprising a screw-threaded shaft mounted in a position parallel to the normal path of movement of such load-supporting means and held against movement therewith but rotatable about its longitudinal axis, a safety holding element carried by said load-supporting means and movable to and from engagement with the threaded portion of said shaft, means normally maintaining said holding element out of engagement with the shaft, and means responsive to slackening of the cable for moving said element into engagement with such portion of the shaft.

5. Means as set forth in claim 1 in which said abutment member comprises a screw shaft, rotatable about its axis but held against unwanted longitudinal displacement and provided with thread means of irreversible pitch, said holding means being engageable with said teeth to serve as a locking dog, and being held against rotation with the shaft whereby the holding means may serve as a nut to enable actuation of the load-supporting means by rotation of the shaft, the screw shaft and taut portion of the cable being arranged in spaced parallel and vertical relation and the holding means comprising a dog pivoted upon the load-supporting means having mutilated teeth movable to and from engagement with the thread means of the shaft by rocking movement of the dog, and a restraining portion engageable with the taut portion of the cable and normally preventing the teeth from engaging the shaft.

6. In combination with a lift mechanism of the cable-operated type comprising a main cable arranged to support a load-supporting means, combined safety means and manually operable means for controlling the descent of such load-supporting means in the event of a cable failure, comprising a screw-threaded shaft mounted in a position parallel to the normal path of movement of such load-supporting means and held against longitudinal movement therewith but rotatable about its longitudinal axis, a safety holding element, means pivotally securing said element to a rigid portion of said load supporting means for movement to and from engagement with the threaded portion of said shaft, said securing means holding said element against rotation about the axis of said shaft, means normally maintaining said element out of engagement with the shaft, and means responsive to a failure of said cable for moving said element into engagement with such shaft portion.

7. In combination with a lift mechanism of the cable-operated type comprising a main cable ar-

7
ranged to support a load-supporting means, combined safety means and manually operable means for controlling the descent of such load-supporting means in the event of a cable failure, comprising a screw-threaded shaft mounted in a position parallel to the normal path of movement of such load-supporting means and held against longitudinal movement therewith but rotatable about its longitudinal axis, a safety holding element, means pivotally securing said element to a rigid portion of said load supporting means for movement to and from engagement with the threaded portion of said shaft, said securing means holding said element against rotation about the axis of said shaft, means normally maintaining said element out of engagement with the shaft, and means responsive to a failure of said cable for moving said element into engagement with such shaft portion, said element being effective as a consequence of the engagement of said element with said shaft to exert a frictional force on said shaft for holding said shaft against rotation about its axis.

8. The combination of claim 6 in which said element comprises a toothed dog and in which a sleeve member fixed relative to said load-supporting means surrounds said shaft with a sliding fit, means pivotally securing said dog relative to said sleeve member so that said shaft is held within predetermined limits of transverse deflection due to the force applied by said dog transversely of said shaft when said dog is in engagement with said shaft.

9. In an elevatable structure, an elevatable platform, a sheave carried by said platform, a supporting member positioned at an elevation above the maximum elevation to which said sheave is to be raised, a main cable having a portion secured to said supporting member and extending

therefrom to said sheave, means for pulling said cable about said sheave whereby said platform is elevated, an elongated member supported against longitudinal movement and positioned parallel to the path of movement of the axis of said sheave during movement thereof with said platform, a dog, means pivotally securing said dog to an element movable with said platform, means normally biasing said dog into a position engageable with said elongated member whereby longitudinal movement of said dog along said elongated member is prevented, and means engageable with the portion of said cable intermediate said sheave and said supporting member and acting to hold said dog in a rotated position out of engagement with said elongated member when said cable portion is taut.

10. The combination of claim 9 in which said elongated member is a rod and is manually rotatable about its longitudinal axis and is provided with helically arranged screw threads of small pitch and in which the portion of said dog engageable with said elongated member has mating screw threads.

11. The combination of claim 10 in which said pivotally securing means holds said dog against rotation about the axis of said elongated member.

RAYMOND F. MANKE.
